Primary Examiner — Stephen M Johnson(74) *Attorney, Agent, or Firm* — Snell & Wilmer LLP(57) **ABSTRACT**

A sighting device replicates the spread pattern of pellets exiting the barrel of a shotgun. The sighting device includes a light source (preferably a laser) and a power source connectable to the light source. The device may also include a mount to attach the sighting device to a shotgun. The sighting device preferably projects a circular pattern of individual light beams wherein the circumference of the circular pattern increases as the light beams move farther from the sighting device to replicate the spread of shotgun pellets. The sighting device may also project a beam of light in the center of the pattern.

SHOTGUN WITH SIGHTING DEVICE

CROSS-REFERENCE TO RELATED APPLICATIONS

This application is a continuation of and claims priority to U.S. patent application Ser. No. 13/707,312, now U.S. Pat. No. 8,844,189 entitled SIGHTING DEVICE REPLICATING SHOTGUN PATTERN SPREAD, filed on Dec. 6, 2012, the disclosure of which is incorporated herein by reference.

FIELD OF THE INVENTION

The present invention relates to a light-emitting sighting device, particularly a laser, that can be mounted on a shotgun and that emits a pattern that replicates the spreading pattern of shotgun pellets after being fired. The disclosures of U.S. Pat. No. 8,127,485 to Moore et al. and U.S. application Ser. No. 12/160,213 to Moore et al. are incorporated herein by reference.

BACKGROUND OF THE INVENTION

It is known to utilize a light beam, such as a laser beam, as a sighting aid for guns. Lasers are the preferred means of generating light beams for weapon sighting because they have comparatively high intensity and can be focused into a narrow beam with a very small divergence angle so they produce a small, bright spot on a target. If mounted properly on a gun, the laser projects a beam of laser light in a direction generally parallel to the gun's bore. When the light beam and bore are properly aligned, the bullet (or other projectile) will strike, or strike very close to, the location of the light beam projected on a target. Such laser sighting devices can be used to target a weapon when using live ammunition or to simulate the actual firing of a weapon whereby the laser beam strikes a target to show where a live round would land.

It was known to use a laser connected to a gun to generate a pattern of light, such as a circular pattern formed by multiple laser light beams with a single laser light beam in the center. The problem with this device is that the light beams were projected outward at an exaggerated angle. Thus, the device may have been useful for centering and aiming a gun firing a bullet, but did not replicate the spread pattern of shotgun pellets after being fired. Thus, such a device did not accurately frame a target with respect to where shotgun pellets would land. This was especially true the farther the target was from the device, since the farther away the target, the greater the shotgun pellet spread.

SUMMARY OF THE INVENTION

The invention is a sighting device for a shotgun (hereafter, sometimes referred to as "sighting device" or "device"), or for a structure replicating a shotgun, which might be used for laser beam target practice are collectively referred to herein as "shotgun." The sighting device includes a light source, which is most preferably a laser. The sighting device may be mounted on or included as part of a shotgun and can be used to aim the shotgun before firing a live round of ammunition, or to simulate the actual firing of a shotgun by the light emanating from the light source showing the area in which pellets from a live shotgun round would land. Once activated, light beams from the sighting device are projected outwardly, preferably in a circular pattern, that expands as the light beams travel farther from the sighting device, thereby replicating the spread pat-

2

tern of pellets fired from a shotgun. The sighting device preferably includes a laser as the light source, a power source connectable to the laser, and a mount for mounting the sight to the shotgun. In one embodiment, the sighting device is attached to a picatinny rail of the shotgun, although it can be attached to or included as part of a shotgun in any suitable manner.

BRIEF DESCRIPTION OF THE DRAWINGS

FIG. 1 is an exploded view of an embodiment of the present invention.

FIG. 1A is a front view of the assembled device shown in FIG. 1.

FIG. 1B is a top view of the device shown in FIGS. 1 and 1A.

FIG. 1C is a rear view of the device shown in FIGS. 1-1B but without the backing or the button yet attached.

FIG. 1D is a rear view of the device shown in FIGS. 1-1C when fully assembled.

FIG. 1E is a rear view of the device shown in FIGS. 1-1D without the backing or the integrated circuit board and showing the laser module biased to one side (the laser biasing spring also is not shown).

FIG. 1F is a partial, cross-sectional top view of a light source biased to one side of the biasing cone (or light source adjustment apparatus).

FIG. 2 is a side, perspective view showing the embodiment of FIG. 1.

FIG. 3 is an alternate side, perspective view of the embodiment shown in FIGS. 1 and 2.

FIG. 4 is a rear, top, perspective view of the embodiment shown in FIGS. 1-3.

FIG. 5 is a front, top, perspective view of the embodiment shown in FIGS. 1-4.

FIG. 6 is a rear, perspective view of a device according to the invention.

FIG. 7 shows an embodiment of a sighting device according to the invention that is mounted to the picatinny rail of a shotgun.

FIG. 8 shows an alternate embodiment of a sighting device of the present invention.

FIG. 9 shows a bottom, rear perspective view of the sighting device of FIG. 8.

FIG. 10 shows a bottom, front perspective view of the sighting device of FIG. 8.

FIG. 11 shows a rear view of the sighting device of FIG. 8.

FIG. 12 shows a front view of the sighting device of FIG. 8.

FIG. 13 shows an exploded view of the sighting device of FIG. 8.

DETAILED DESCRIPTION OF PREFERRED EMBODIMENTS

Turning now to the drawings where the purpose is to describe a preferred embodiment of the invention and not to limit same, FIGS. 1-7 show a preferred embodiment of a sighting device 10 according to the invention. Device 10 as shown is a laser sight, but could be any structure that includes a light source and one or more power sources connectable to the light source and that can simulate the spread pattern of shotgun pellets exiting the barrel of a shotgun.

Preferably, device 10 is configured to be mounted on a shotgun 11, and most preferably on a picatinny rail of the shotgun 11. A picatinny rail 9 (best seen in FIG. 7) is known in the art and used to connect accessories to gun. As shown, picatinny rail 9 is on the top of the shotgun barrel.

Device 10 could also be mounted to or formed in the shotgun in any other suitable, fashion that allows the light source of device 10 to be accurately projected along the longitudinal axis of the shotgun barrel 13, and/or along the longitudinal axis of a light source 20.

Device 10 includes a light source 20, a power source 30 and a housing 200 that includes a mount 102, which as shown has a first leg and a second leg, which are not shown here, but preferably have the same structures as legs 1002A and 1002B discussed below, that fit onto picatinny rail 9.

Light source 20 has a first end 20A (through which light can be emitted), is preferably a visible-light laser module, but could be any light source, including a light emitting diode ("LED") flashlight (as used herein "flashlight" means any source of visible light other than a laser) or an infra-red light source (such as an infra-red LED or infra-red laser). In the embodiment shown light source 20 is a red-light, 650 nanometer, 3.3 mm diode, visible laser, and the laser module has an overall length of about 14 mm and a diameter of about 4.5 mm. Any suitable laser/laser module may be used, however. A biasing spring 24 is attached to second end 20B to bias light source 20 towards first end 20A when device 10 is assembled. Light source 20 includes a diffraction lens (not shown) that converts the single laser beam generated by light source 20 into multiple, individual beams of light. Diffraction lenses are known to those skilled in the art. In embodiments of the present invention, the diffraction lens can be assembled as part of light source 20 or be positioned outside of light source 20.

The multiple light beams generated by the diffraction lens are spread apart so as to define an area between them. The area can be of any suitable shape for replicating the area in which pellets exiting a shotgun would occupy. It is most preferable that the area defined by the multiple light beams is circular, but it could also be triangular, oval, rectangular, hexagonal, octagonal or of any suitable shape. In one preferred embodiment there are at least three light beams defining the area, and most preferably eight beams of light defining the area, even though any number of light beams of three or more can be utilized. Additionally, a complete, uninterrupted pattern of light could be created to form an area between the pattern.

The diffraction lens directs each of the multiple beams of light outward with respect to the longitudinal axis of the light source 20, as shown in FIG. 7. In one embodiment each of the multiple beams is directed outward at 1.7 degrees as measured from the longitudinal axis of the laser 20. Any suitable outward direction may be used, however, and is based on the size and type of shotgun, so that the pattern of pellet spread for that shotgun is accurately replicated.

The diffraction lens may also create one or more other light beams inside the area, and preferably creates a single light beam in the center of the area formed by the multiple beams.

Power source 30 can be any suitable power source for light source 20, and is preferably an electric power source and most preferably a portable, electrical power source such as a battery or multiple batteries. The embodiment shown uses four 1.5V silver oxide LR626 batteries 32, although any suitable batteries or other power source may be used.

Device 10 as shown further includes a housing 200, a light source adjustment apparatus 300, an integrated circuit board 400, a backing 500, and a battery cap 600. The purpose of housing 200 is to retain light source 20 and power source 30 and mount them to a gun, and to selectively connect power source 30 to light source 20. Any suitable structure or structures may be used for this purpose.

Housing 200 is preferably made of metal injection molded stainless steel (MIM), but could be made of any suitable

material, such as another metal (for example, MIM carbon steel or extruded aluminum) or plastic. Housing 200 has a first end 200A, a second end 200B and includes a first canister 202 and a second canister 230. First canister 202 is configured to receive and retain the light source 20 (which is preferably a laser module), which as shown is first positioned in light source adjustment apparatus 300. Once so positioned, apparatus 300, with light source 20 inside, is positioned in and retained in canister 202.

As shown, canister 202 has an outer surface 204, a first rib 206, a second rib 208, an inner cavity 210 in which apparatus 300 and light source 20 are retained, and an opening 212 through which the light source 20 can emit light. Canister 202 also includes an aperture 206A that extends through rib 206 to inner cavity 210 and an aperture 208A that extends through rib 208 to inner cavity 210. Each of apertures 206A and 208A are configured to receive a moveable screw or screw 225 (hereafter referred to as "set screw" or "set screws," which are preferably socket-head set screws). The purpose of rib 206 and rib 208 (each of which project outward about 0.075") are to provide additional area to support set screws 225. Alternatively, a raised portion (described, for example with respect to device 10', device 1000 and device 2000) may be used in place of rib 206 and/or 208. Other structures may be used for this purpose or no such structure may be used.

Second canister 230 as shown is spaced apart from first canister 202 and is configured to receive and retain the power source 30. Canister 230 as shown has an outer surface 234, an inner cavity 240, a first end 242 and a second end 244. Second end 244 is configured to open in order to add or change power source 30. In the embodiment shown second end 244 includes internal threads (not shown) that mate with threads on power source retention cap 600 to allow cap 600 to be screwed onto end 244 and screwed off of end 244 in order to add or remove power source 30 from canister 230.

Housing 200 also includes a connective portion 270 that connects first canister 202 and second canister 230. Connective portion 270 has a bottom surface 272 and a mount 102 attached to or integrally formed with bottom surface 272. Mount 102 includes the previously described first leg and second leg (not shown here) for connecting to picatinny rail 9, although any suitable structure or structures may be used for this purpose.

A light source adjustment apparatus (or "LSAA") 300 is for retaining the light source 20 when it is positioned in housing 200 and for assisting in positioning light source 20. LSAA 300 serves two purposes: (1) it absorbs the recoil of a gun to which device 10 is mounted thereby enabling light source 20 to remain in a relatively stable position, and (2) it enables a user to adjust the position of light source 20. As shown in FIG. 1, LSAA 300 is generally conical with a first, smaller diameter end 302 and a second, large diameter end 304. It is preferably comprised of an elastomeric material, such as neoprene rubber, of about a 60 Shore A to absorb shock, but can be made of any suitable material. It has an opening 308 configured to receive light source 20. As previously described, LSAA 300 fits into inner cavity 210 of first canister 202. Instead of LSAA 300, the light source 20 may be biased towards set screws 225 (described below) by springs (not shown).

When device 10 is assembled, the position of light source 20 can be adjusted utilizing set screws 225. LSAA 300 is shaped to be biased towards apertures 206A and 208A and, as one or both set screws 225 are tightened, the set screw(s) pushes against LSAA 300 and moves it (in this embodiment) either sideways and/or vertically thereby adjusting the position of light source 20. Alternatively, springs inside cavity 210

bias the light source **20** towards each of the set screws **225**, and as the set screws are tightened, they push against the light source **20** and overcome the force of the springs to move light source **20**.

Integrated circuit board **400** is configured to be received and mounted on second end **200B** of housing **200**. The basic purpose of board **400** is to connect the power source **30** to the light source **20** and any suitable structure or device can be used for this purpose. Board **400** is preferably plastic and includes a push button switch **402**, an integrated circuit **404** and two through screw holes **406**. Current is transferred via board **400** to laser module **20**. Board **400** is designed for negative switching wherein power is generated from the negative side of power source **30** (which are batteries in this embodiment) and through spring **24** of light source **20** in this embodiment. Integrated circuit **404** allows for the pulsed delivery of power to light source **20** (preferably about 1,000 cycles per second, and preferably pulsing at a 50% on duty rate) in order to save power and power source life, although the delivery of power need not be pulsed, or can be pulsed in any suitable manner. In this embodiment, the light source has between a 8 and 15 milliamp draw, and most preferably less than a 10 milliamp draw, of current when in use and utilizing the 1,000 pulses per minute delivery of current to light source **20**.

A button **450** is of any suitable shape to fit with push button switch **402** and backing **500**, described below. Button **450** is for enabling a user to selectively activate switch **402** thus turning the light source **20** off and on, and any suitable device or structure can be used for this purpose.

Backing **500** is preferably plastic and its purpose is to hold integrated circuit board **400** to housing **200** and to protect integrated circuit board **400** and the other components inside of housing **200**. Backing **500** has a first side **500A** configured to fit over canister **202** at end **200B** and a second side **500B** configured to fit over end **242** of canister **230**. It further includes an opening **502** through which button **450** projects so it can be pressed by a user to turn light source **20** on and off, and openings **506** that align with screw holes **406** and screw retainers **250**. Screws **510** are then received through openings **506** and screw holes **406**, and are threaded into retainers **250** to hold device **10** together.

Power source retention cap **600** has a threaded end **602** and an end **604** that can be tightened or loosened by a user. The purpose of cap **600** is to selectively open and close second canister **230** to allow power source **30** to be removed or inserted and any structure capable of performing this function can be used. Cap **600** has a cavity **606** that receives a spring **608** to bias batteries **32** away from spring **608**. Spring **608** contacts the positive side of the power source **30** and grounds it to the housing **200** through cap **600**. As explained below, a rubber biasing collar **620** may also be utilized with cap **600**.

Turning now to FIGS. 8-12, a device **1000** according to an aspect of the invention is shown. The materials, internal structure and function, except for differences in size and shape, and those described herein, are the same as those described for device **10**. Device **1000** includes a housing **1002** that retains a light source **1020** (which is preferably a laser), which is the same as light source **20**, and preferably a diffraction lens, which is the same as the previously described diffraction lens for device **10**. The diffraction lens may be formed as part of light source **1020** or positioned outside of it so that a beam of light exiting light source **1020** is diffracted into multiple beams in the manner previously described and/or subsequently claimed herein. Alternatively, the multiple beams can be created in other ways.

An opening **1022** retains a set screw (not shown) that can be used to adjust the position of sighting device **1020** in the sideways direction. Another opening (not shown) is on the top surface **1081** of housing **1002** and retains another set screw (not shown), which can also be used to adjust the position of sighting device **1020** vertically.

A power source **1090** is retained within housing **1002** and is preferably three silver oxide 1.5V coin batteries connectable to light source **1020** in the same manner as previously described with respect to sighting device **10**. Housing **1002** includes a removable cap **1004** that covers a cavity that retains the power source. Cap **1004** is held in place by two fasteners **1006**.

Housing **1002** includes a first leg **1002A** and a second leg **1002B**, that are used to grip a picatinny rail, such as rail **9** shown in FIG. 7. First leg **1002A** has a mating portion **1030A** and an opening **1035A**, and second leg **1002B** has a mating portion **1030B** and an opening **1035B**. A fastener **1050** is positioned between first leg **1002A** and second leg **1002B**. First end **1056** of fastener **1050** is adapted for receiving the fastener **1050** and is retained in opening **1035A**. Fastener **1050** has a threaded body **1054** that is threadingly received in opening **1035B**, preferably by being threadingly received in a nut **1038** that is retained in opening **1035B**. As fastener **1050** is tightened, it draws together mating portions **1030A** and **1030B** to tighten them against a picatinny rail. Fastener **1050** can then be loosened to remove device **1000** from the picatinny rail.

Turning now to FIGS. 9-13, the back surface **1040** of device **1000** includes two fasteners, **1078** and **1080**, which as shown are hex head nuts with washers that are received in opening **1090** of circuit board **4000**.

Light source **1020** has a first end **1020A** (through which light can be emitted), is preferably a visible-light laser module, but could be any light source, including a light emitting diode ("LED") flashlight (as used herein "flashlight" means any source of visible light other than a laser) or an infra-red light source (such as an infra-red LED or infra-red laser). In the embodiment shown light source **1020** is a red-light, 650 nanometer or 635 nanometer, 3.3 mm diode, visible laser, and the laser module has an overall length of about 14 mm and a diameter of about 4.5 mm. Any suitable laser/laser module may be used, however. A biasing spring **24** is attached to second end **1020B** to bias light source **1020** towards first end **1020A** when device **1000** is assembled. Light source **1020** preferably includes a diffraction lens (not shown) that converts the single laser beam generated by light source **1020** into multiple, individual beams of light. In embodiments of the present invention, the diffraction lens can be assembled as part of light source **1020** or be positioned outside of light source **1020**.

As with device **10**, the multiple light beams generated by device **1000** are spread apart so as to define an area between the light beams. The area can be of any suitable shape for replicating the area in which pellets exiting a shotgun would occupy. It is most preferable that the area defined by the multiple light beams is circular, but it could also be triangular, oval, rectangular, hexagonal, octagonal or of any suitable shape. In one preferred embodiment there are at least three light beams defining the area, and most preferably eight beams of light defining the area, even though any number of light beams of three or more can be utilized.

The diffraction lens, or other method of generating multiple light beams, directs each of the multiple beams of light outward with respect to the longitudinal axis of the light source **1020**. In one embodiment each of the multiple beams is directed outward at 1.7 degrees as measured from the

longitudinal axis of the laser 20. Any suitable outward direction may be used, however, and is based on the size and type of shotgun, so that the pattern of pellet spread for that shotgun is accurately replicated.

The light source may also create one or more other light beams inside the area, and preferably creates a single light beam in the center of the area formed by the multiple beams.

Power source 1090 can be any suitable power source for light source 1020, and is preferably an electric power source and most preferably a portable, electrical power source such as a battery or multiple batteries. The embodiment shown uses 3 silver oxide 1.5V silver oxide coin batteries, although any suitable batteries or power source may be used.

Device 1000 as shown further includes a housing 2000, a light source adjustment apparatus 3000, an integrated circuit board 4000, a canister 5000 having a first cavity 5002, a second opening 5004, a first end 5006, a second end 5008, and a dividing wall 5010. First cavity 5002 retains light source 1020 and light source adjustment apparatus ("LSAA") 3000, wherein light source adjustment apparatus 3000 is first positioned over light source 1020 prior to being positioned in first canister 5002. Second cavity 5004 retains power source 1090. The ultimate purpose of housing 2000 is to retain light source 1020 and power source 1090 and mount them to a gun, and to selectively connect power source 1090 to light source 1020. Any suitable structure or structures may be used for this purpose.

Housing 2000 is preferably made of injection molded plastic, but could be made of any suitable material, such as another metal (for example, MIM carbon steel or extruded aluminum). Housing 2000 has a first end 2000A, a second end 2000B and includes a cavity 2001 that retains canister 5000. Canister 5000 is preferably made of aluminum or other conductive material so as to complete the connectivity required for the proper functioning of the circuit board 4000, when circuit board 4000 is pressed against end 5008 of canister 5000 when device 1000 is fully assembled.

Housing 2000 has a first end 2000A with an opening 1020C to permit light to be emitted from light source 1020 (preferably through a diffraction lens), and an opening 2001A that retains cap 1004 and permits access to the power source 1090 to permit replacement of the power source.

As discussed above, housing 2000 also includes an aperture 1022 that extends to either LSAA 3000 or light source 1020. A second aperture (not shown) on surface 1081 also extends to either LSAA 3000 or light source 1020. Each of these apertures are configured to receive a moveable screw (hereafter referred to as "set screw" or "set screws," which are preferably socket-head set screws), which are not shown for this embodiment.

An opening 5004A in the first end of canister 5004 is preferably threaded (not shown) so that it can receive cap 1004, which is threaded. A depression 1005 is formed in cap 1004 in order to screw cap 1004 onto end 5004A. Cap 1004 can be removed to access and replace power source 1090.

A light source adjustment apparatus (or "LSAA") 3000 is for retaining the light source 1020 when it is positioned in canister 5000 and for assisting in positioning light source 1020. LSAA 3000 absorbs the recoil of a gun to which device 1000 is mounted thereby enabling light source 1020 to remain in a relatively stable position. As shown in FIG. 13, LSAA 3000 may be generally conical and slides over light source 1020. It is preferably comprised of an elastomeric material, such as neoprene rubber, of about a 60 Shore A to absorb shock, but can be made of any suitable material. As previously described, LSAA 3000 fits into cavity 5002 of canister 5000. Instead of LSAA 3000, or in addition to LSAA 3000, the light

source 20 may be biased towards the set screws (not shown in this embodiment) by springs (not shown).

When device 1000 is assembled, the position of light source 1020 can be adjusted utilizing the set screws (not shown). LSAA 3000 and/or the springs (not shown) can bias the light source 1020 towards the set screws. As one or both of the set screws are tightened, the set screw(s) pushes against the LSAA 3000 or the light source 1020 and moves the light source 1020 either sideways and/or vertically thereby adjusting the position of light source 1020.

Integrated circuit board 4000 is configured to be received and mounted on plate 1070 of housing 2000. The basic purpose of board 4000 is to connect the power source 1090 to the light source 1020 and any suitable structure or device can be used for this purpose. Board 4000 is preferably plastic and interacts with two push button switches 1072 and 1074. Board 4000 includes an integrated circuit (not shown) and two through screw holes 1090. Current is transferred via board 4000 to laser module 1020. Board 4000 is designed for negative switching wherein power is generated from the negative side of power source 1090 (which are batteries in this embodiment) and through spring 1024 of light source 1020 in this embodiment. In the preferred embodiment of device 1000, the integrated circuit allows for continuous delivery of power to light source 1020.

In this embodiment, spring 1024 is connected to the back of laser module 1020 in any suitable manner, and is then connected to board 4000, preferably by soldering. Spring 1024 acts as the negative contact for module 1020 to board 4000 and also allows module 1020 to move freely back and forth axially and in all directions. In this manner, module 1020 can freely be adjusted by the previously described set screws.

Buttons 1072 and 1074 are preferably identical and of any suitable shape to fit in the openings in plate 1070 and switch power off or on to light source 1020. Each button 1072 and 1074 operates independently and is for enabling a user to selectively activate a switch to turn the light source 1020 off or on, and any suitable device or structure can be used for this purpose.

Device 1000 also preferably includes a backing, such as backing 5000, which is preferably plastic. Although not shown here, the backing is of a suitable size, shape and material to function the same as previously described backing 500.

A sighting device according to the invention may be mounted to a shotgun in any suitable manner utilizing any suitable structure.

Having thus described some embodiments of the invention, other variations and embodiments that do not depart from the spirit of the invention will become apparent to those skilled in the art. The scope of the present invention is thus not limited to any particular embodiment, but is instead set forth in the appended claims and the legal equivalents thereof. Unless expressly stated in the written description or claims, the steps of any method recited in the claims may be performed in any order capable of yielding the desired result.

What is claimed is:

1. A gun including:
  - (a) a muzzle,
  - (b) a bore,
  - (c) a trigger, and
  - (d) a sighting device for framing a target to be fired at with the gun, the sighting device including a first light source that is a single laser module and a power source connectable to the first light source, the first light source having a first mode in which it emits light and a second mode in which it does not emit light, the first light source ema-

nating a single beam of light that passes through a diffraction lens which splits the single beam into a pattern of three or more light beams defining an area inside the pattern and a separate beam of light inside the pattern, wherein the area of the pattern increases as the beams of light move farther from the first light source.

2. The gun of claim 1 that is a shotgun.
 3. The gun of claim 2 wherein the sighting device includes a mount for attaching to a picatinny rail of the shotgun.

4. The gun of claim 3 wherein the mount includes a first leg configured to fit into a first side of the picatinny rail and a second leg opposite the first leg, the second leg configured to fit into a second side of the picatinny rail.

5. The gun of claim 4 that further includes a tightener to draw the first leg and second leg closer together in order to tighten the mount onto the picatinny rail.

6. The gun of claim 5 wherein the tightener comprises a threaded fastener that extends from the first leg to the second leg, the fastener having a head at the first leg for receiving a tool, and being threadingly received in the second leg, so as the tool turns the fastener head in a first direction, the fastener is tightened in the second leg, which forces the first leg and second leg closer together, and as the tool turns the fastener in a second direction, the fastener is loosened in the second leg and the first leg and second leg move farther apart.

7. The gun of claim 2 wherein the muzzle has a longitudinal axis, and the sighting device is aligned with the longitudinal axis so the light emanating from the sighting device projects a pattern that replicates the pattern of shotgun pellets exiting the muzzle of the shotgun.

8. The gun of claim 1 wherein the single beam of light passes through the diffraction lens which splits the single beam into eight beams of light and the area is in the center of the eight beams of light, wherein the area of the pattern increases as the beams of light move farther from the first light source.

9. The gun of claim 8 wherein the diffraction lens splits the single beam into a pattern of eight or more light beams defining an area inside the pattern and a separate beam of light in the center of the area, wherein the area of the pattern increases as the beams of light move farther from the first light source.

10. The gun of claim 1 wherein the light beams exit the diffraction lens at an outward angle of 1.7 degrees as measured from a longitudinal axis of the first light source.

11. The gun of claim 1 wherein the first light source is a visible laser module.

12. The gun of claim 1 wherein the first light source is an infra-red laser module.

13. The gun of claim 1 that further includes a light source adjustment apparatus for mechanically adjusting the position of the first light source, wherein the light source adjustment apparatus comprises one or more set screws and springs that bias the first light source towards each set screw.

14. The gun of claim 13 wherein the first light source further includes a housing with a plurality of apertures and a set screw threadingly received in each aperture, the set screws for adjusting the position of the first light source.

15. The gun of claim 1 wherein the first light source is a LED infra-red light module.

16. The gun of claim 1 wherein the power source is one or more batteries.

17. The gun of claim 1 wherein the power source is spaced apart from the first light source.

18. The gun of claim 1 wherein the power source is positioned under the first light source.

19. The gun of claim 1 wherein the sighting device includes a mount that may be pressure fit into a slot on the gun.

20. The gun of claim 1 wherein the sighting device includes a mount for attaching to a picatinny rail of the gun.

21. The gun of claim 1 wherein the sighting device includes a first canister and a second canister, wherein the first canister includes the first light source, and the second canister includes the power source.

22. The gun of claim 1 wherein the first light source pulses when it emits light.

23. The gun of claim 1 wherein the area is selected from one of the group consisting of: circular, oval, triangular, rectangular, hexagonal and octagonal.

24. The gun of claim 1 wherein the sighting device is mounted on the gun.

25. The gun of claim 1 wherein the sighting device is integrally formed with the gun.
